them, which is melted or softened when the heated pins are pushed therein, hardens.

It is to be understood that the drawings are merely illustrative and that variations in color, size and general cross-sectional shape of the candles may be varied as desired.

What I claim is:

A decorative candle having a comparatively flat wax body in the form of a character selected from the group consisting of the numerals and the letters of the alphabet; a centrally-disposed, upstanding, elongated, flat wick embedded therein with one lateral, marginal edge of said wick exposed on the top of said candle and forming a substantially uninterrupted outline of said character; and drip-catching means comprising a sheet of metal foil having a reflective upper surface and conforming generally in outline to the outline of the base of said character but project-

ing laterally beyond said base; and means securing said foil to said base.

WILLIAM B. BYRNES.
